(No Model.)

L. JOHNSON & L. FRIDLUND.
FABRIC OR GOODS HOLDER.

No. 554,934.

Patented Feb. 18, 1896.

UNITED STATES PATENT OFFICE.

LEWIS JOINSON AND LEWIS FRIDLUND, OF WILLMAR, MINNESOTA.

FABRIC OR GOODS HOLDER.

SPECIFICATION forming part of Letters Patent No. 554,934, dated February 18, 1896.

Application filed June 24, 1895. Serial No. 553,867. (No model.)

To all whom it may concern:

Be it known that we, LEWIS JOINSON and LEWIS FRIDLUND, citizens of the United States, residing at Willmar, in the county of Kandiyohi and State of Minnesota, have invented certain new and useful Improvements in Fabric or Goods Holders, of which the following is a specification, reference being had therein to the accompanying drawings:

10 This invention aims to facilitate the bolting or reeling of textile fabrics and like goods which are stored in a compact form by being wound upon itself or a core, and to enable the ready and convenient handling of the 15 same when it is required to display the goods or measure off a quantity for a customer.

With these and other objects in view, which will become apparent as the nature of the invention is unfolded, the improvement consists 20 of the novel features which hereinafter will be more fully set forth and claimed, and which are shown in the accompanying drawings, in which—

Figure 1 is a side elevation of a device constructed in accordance with and embodying the essence of the present invention, the full lines showing the holder resting upon the counter and the dotted lines showing the holder in an elevated position. Fig. 2 is a 30 detail view showing the base by means of which the device is secured to the counter or other support. Fig. 3 is a top plan view of the base.

The base 1 is expanded at its lower end and 35 is apertured to receive screws or like fastenings 2 by means of which the device is fixedly attached to a counter 3 or other support. A head 4 has a depending pintle 5, which is mounted in a vertical opening formed in the 40 base 1, and the lower end of this pintle is reduced and threaded and fitted with a nut 6, by means of which the head 4 is held to the base 1. Obviously any means may be employed for securing the head 4 and base 1 45 together and which will admit of the said head turning upon the base. The head 4 is preferably globular in form and is cleft so as to receive the inner expanded end 7 of an arm 8, and which is pivoted to the head 4 by means 50 of the pin 9. Two diagonally-opposite corners of the pivotal end of the arm 8 are extended and formed with pins 9^a, which are

adapted to pass through openings in the foot 10 of the head 4 and extend into depressions 11 in the top side of the base 1, thereby locking the head 4 and the base 1 in the required adjusted position. It will be understood that there will be a series of depressions 11 in the top side of the base 1, and when it is required to turn the head 4 upon the base the arm 8 60 is moved so as to withdraw either of the pins 9^a out of engagement with the depressions 11, and the said arm and head are turned until the desired position is obtained when, by lowering the arm 8 into a horizontal position, as 65 shown by the full lines in Fig. 1, or by elevating it into a vertical position, as shown by the dotted lines in the said figure, the proper pin 9^a will enter the desired depression in the base 1 and hold the arm and head in the located position.

A bearing 12 is formed at the outer end of the arm 8 and has an extended portion 13 to form a foot to rest upon the counter or other support and relieve the arm 8 of all weight 75 and strain when the device assumes a horizontal position, and this bearing is longitudinally bored so as to receive the spindle 14 pendent from the lower side of a table or platform 15. This spindle 14 has its lower or outer 80 portion threaded for a short distance to receive a nut 16, by means of which it is held within the bearing 12, and the end 17 exterior to the nut 16 is made angular for the reception of a crank or other instrument, by means 85 of which the spindle 14 is adapted to be rotated on the bearing 12 for the purpose of winding up the fabric or goods to be bolted. A boss 18 is formed or attached to the lower side of the table 15 and is transversely bored 90 to receive and form a bearing for the shaft 19, which has its inner portion 20 threaded for a short distance and upon which threaded portion is mounted a movable jaw 21 and which is actuated by rotating the said shaft 19 within 95 the boss 18. An annular groove 21' is formed in the shaft 19 between its ends, and a key 22, driven into an opening in the boss 18, fits in the said annular groove 21' and holds the shaft 19 from longitudinal movement within the 100 boss 18. A crank 23 is fitted to the outer end of the shaft 19 and is held to the latter by means of a key 24. A stationary jaw 25 extends at right angles from the table 15 and is

parallel with the jaw 21, and these two jaw are preferably roughened on their opposing or clamping faces, so as to bind firmly upon the sides of the core or board upon which the fabric or goods is wound.

5 When it is required to unwind a piece of goods or fabric the latter is fitted upon the jaws 21 and 25, or if it has a core, such as the thin boards generally used as a foundation upon 10 which fabrics are wound, the said core is clamped between the jaws 21 and 25 by operating the screw 19, as will be readily understood. By pulling upon the end of the fabric or goods the latter will be unwound by reason of the table or platform 15 rotating upon the bearing 12. To suit the convenience of the salesman the table can be made to occupy a horizontal or a vertical position, as shown by the full and dotted lines in Fig. 1, and 15 20 when it is required to rewind the fabric or goods a crank is fitted to the angle end 17 of the spindle 14 and is turned so as to rotate the table 15, whereby the desired result is attained.

25 Having thus described our invention, what we claim, and desire to secure by Letters Patent, is—

1. A fabric or goods holder comprising a base, a head constructed to be secured upon 30 the base at different angles, an arm having pivotal connection with the said head and a table rotatably mounted upon the said arm and provided with means to support the goods or fabric to be wound and unwound, substantially as set forth.

2. In a fabric or goods holder, the combination with a base, a head constructed to be secured upon the base at different angles, and a table for supporting the fabric or goods, of 40 an arm carrying the said table and having pivotal connection with the said head and provided with a locking-pin to engage with a depression in the said base and secure the arm and head in the required position, substantially as set forth.

45 3. In combination a base, a head constructed to be secured upon the base at different angles, and a fabric or goods supporting arm having a pivotal connection with the said 50 head and having locking-pins at diagonally-

opposite points and which are adapted to engage with depressions in the said base so as to secure the said arm in any adjusted position, in either a vertical or horizontal position, substantially as set forth for the purpose described. 55

4. In combination a base, a supporting-arm pivotally connected with the base at one end and having a bearing at its opposite end, a table for receiving and supporting the fabric 60 or goods, and a spindle extending from the table and journaled in the said bearing and having its ends made angular to receive a crank by means of which the table is rotated, substantially as set forth for the purpose described. 65

5. In a fabric or goods holder, the combination of a supporting-arm having a bearing, a table provided with a boss and a spindle the latter being journaled in the said bearing, and 70 having its outer end made angular for the reception of a crank, a shaft journaled in the said boss and having a threaded portion, a movable jaw mounted upon the threaded portion of the shaft and a companion jaw to act 75 in opposition to the movable jaw for clamping the core between them, substantially as set forth.

6. The herein-specified fabric or goods holder, comprising a base, a head constructed to 80 be secured upon the base at different relative angles, an arm having pivotal connection with the said head and formed at its outer end with a bearing and having diagonally-disposed locking-pins at its pivotal ends to engage with 85 depressions in the base to secure the head in any adjusted position, a table having a boss and a spindle, the latter journaled in the said bearing and having its end constructed to receive a crank, a shaft journaled in the boss 90 and having a threaded portion, and a stationary and a movable jaw, substantially as set forth for the purpose described.

In testimony whereof we affix our signatures in the presence of two witnesses.

LEWIS JOHNSON.
LEWIS FRIDLUND.
